UNITED STATES PATENT OFFICE

2,097,558

MACHINE FOR OPERATING UPON THE
HEEL-PORTIONS OF SHOESFrancis L. Brandt, Wakefield, Mass., assignor to
United Shoe Machinery Corporation, Paterson, N. J., a corporation of New Jersey

Application December 30, 1935, Serial No. 56,733

23 Claims. (Cl. 144—93)

My invention relates to shoe-machines and more particularly to those for operating upon the heel-portions of shoes. An instance of work to which the apparatus is applicable is found in the drilling through the heel-seat-portion of a shoe into an attached heel for the insertion of a heel-securing screw. Claims generic to the present invention are included in Letters Patent of the United States No. 2,054,068, Brandt, September 15, 1936.

In the heelng of shoes, it may be desired, after a heel has been adhesively attached or nailed and the work is off the last, to further strengthen the connection by the insertion of a permanent screw. My invention has as an object the accomplishment of such an end in an effective manner, by simple means convenient for the operator to use. This object is attained by associating with a rotatable tool, as a drill by which a screw-receiving opening is formed in the work, or a screw-driver by which a threaded fastening is inserted, a member which may engage the work and support and guide it, said member being movable along the tool. This member preferably surrounds the tool and has a transverse contour substantially that of the interior of the counter-portion of a shoe-upper or of the heel-portion of a last. A shoe off the last may be applied to such a work-engaging member and, because of the form of the member, may be positioned by contact with it both longitudinally and laterally of the shoe and, also, toward and from the tool to receive the action thereof. Since the engaging member normally surrounds the tool, the operator is protected against injury by contact with it, and the tool itself is less liable to be broken. Then, upon the application of the work, the member yields, as against a spring, to permit the tool-operation to be performed. To avoid accidental displacement of the engaging, positioning and protecting member, it may be locked normally in its inactive relation by a member movable upon it, this member being released by contact of the work. To determine the point at which the tool is to act, means is preferably provided for varying the relation of the work to it. In the present instance, this means is shown as a screw which is threaded through the locking member and which contacts with the work. By adjustment of this screw or other positioning means, the shoe may be shifted lengthwise of the sole to bring different points into registration with the tool. If desired, a clearing device for a drill-flute may be associated with the engaging member, and I

have also provided for the attachment of a countersink to the drill, this countersink having a chip-disposing groove. In the particular form of the invention which I have chosen to illustrate, a drill rotates within a tube extending from a support, and the engaging member, furnished by a shoe-entering block, is movable longitudinally of the tube. Preferably, a spring surrounds the tube between the support and block, and there is a lever for locking the block against movement tending to compress the spring as the work is presented to the drill. To allow the block to be removed and replaced readily, as when a change of size is desirable, a latch retains the block separably upon the support.

In the accompanying drawing, illustrating a particular embodiment of the invention,

Fig. 1 shows it in side elevation, with the more essential elements sectioned upon a central, vertical plane;

Fig. 2 is a partial view similar in character, with the elements as related at the completion of a drilling operation, and with a countersink in place upon the drill;

Fig. 3 is a partial end elevation looking from the right in Fig. 1, and

Fig. 4 is a vertical, sectional detail illustrating a chip-clearing device for the drill.

Upon a base-plate 10 a motor 12 is mounted, the shaft of this motor having secured to it a chuck 14 fixed in place by a set-screw 16. In this chuck, a drill 18 is held by a set-screw 20, there being a substantial space between the opposed ends of the drill and motor-shaft, so said drill may be adjusted longitudinally of its axis to provide for boring to different depths, as will later appear. Rising from the base below the motor-shaft is an upwardly and outwardly inclined bracket 22 furnishing a support for the elements peculiar to the present invention.

Fixed in the bracket and surrounding the drill for a part of its length is a horizontal tube 24, which provides an auxiliary supporting portion of the bracket. Outside this tube and the drill and movable along them is a block 26, which, upon engagement by the work, serves to position it initially with relation to the drill and to support and guide it during the boring operation. This block, considered transversely of its outer work-engaging end, has substantially the contour of the heel-end of a last; that is, its side-walls are complementary to the counter-portion of a shoe and its end-wall to the heel-seat-portion of the insole. The block may have its side corresponding generally to the breast-line, fac-

ing upwardly, and it is guided for longitudinal movement by a tube 28 extending inwardly from it and telescoping within the support-tube 24. At the inner and upper edge of the block is a 5 horizontal surface 30 sliding along an opposed surface 32 of the support, it thus being held against rotation about its axis. A vertical surface 34 upon the support limits the inward travel of the block and, therefore, the depth to which 10 the drill may enter the work, a change in the depth of drilling being effected by the setting of the tool in the chuck 14, as previously described. At 36, the block is normally restrained against movement of separation from the support by a 15 latch 38, sliding vertically in said support and urged into the path of the block by a spring 40. By raising the latch, the block may readily be removed from the machine and replaced by another, as when it is desired to obtain closer conformity with sizes of shoes being operated upon. 20

Within the block-tube 28, and therefore within the support-tube 24 and the block itself, is a passage 42 through which the drill 18 passes, contact of the block with the latch 38 locating the 25 point of the drill, in its inactive relation, about in the plane of the end-wall of the block. An outwardly tapered throat 44 at the end of the passage 42 about the end of the drill facilitates the discharge of the chips which are produced. 30

In the normal position, as appears in Fig. 1, in which the block with its tube 28 and the support-tube 24 entirely surround the rotating drill and prevent injury by or to it, said block is yieldably held against the latch 38 by a helical spring 46 35 encircling the two tubes and abutting at its ends upon the support and the block. Accidental inward displacement of the block when no work is upon it, which would leave the end of the drill unprotected, is prevented by a locking member 40 in the form of a lever 48 fulcrumed at the lower side of the block 26 between spaced walls and having an inner end-surface 50 engaging the support. The opposite outer extremity of the locking lever extends below the block, so, when a 45 shoe is applied for the drilling operation, the rear of its counter-portion will swing the lever upwardly against a spring-plunger 52, which urges it into locking position, this contact with the work freeing the surface 50 of the lever from the support. The block may now be forced along the 50 drill to produce the desired bore. To alter the point of entrance of the drill into the insole longitudinally of the shoe, as may be desirable for certain changes of size, the lever 48 may have 55 threaded in a substantially vertical direction in its outer end a screw 54, the head of which will receive contact of the rear of the counter-portion of an applied shoe. By causing this screw to project for different distances from the lever, 60 the position of the work may be determined variably. The portion of the lever through which the screw passes is shown as divided at 56 to give a binding effect and thus hold it against chance displacement. 65

In using the machine, it may be assumed that the work consists of a shoe S from which the last has been removed and which has a heel H attached, as by nails N or by an intermediate layer of an adhesive, or by both of these securing 70 means. A drill 18 of the proper diameter is set in the chuck 14 at a point which will penetrate the heel-seat of the shoe and enter the heel to the chosen depth when the block 26 is in contact with the support-surface 34. Taking a shoe 75 with the heel-end down, the operator applies it

to the block, the sides of which engage the counter-portion to position it laterally so the point of the drill is approximately opposite the center line of the shoe. Pressing upwardly, the locking lever 48 is released by the engagement of the shoe, which, at the same time, determines the relation of the shoe longitudinally in accordance with the setting of the screw 54. With the work thus located, inward pressure upon it compresses the spring 46 and causes the constantly rotating drill to act upon the work. The operator thereupon withdraws the work, and the block is returned to its initial position by the spring and locked by the now released lever 48. The chips produced may gather to some extent in the throat 44, to be freed when the work is removed, while some may enter the passage 42, traveling along the ample space which this provides and being discharged at the rear of the support-tube 24. 10 If it is found that clogging of the drill occurs, the flute may be cleared by the device illustrated in Fig. 4. Here, a cylindrical member 60 surrounds the drill within the outer end of the tube 28 and has a helical projection 62 entering the drill-flute. Since the clearing member is connected to the drill only by the entrance of the projection into the flute, it may be moved freely in an axial direction and thus applied or removed without disturbing the drill or the block 26. An internal shoulder 64 upon the tube prevents inward travel of the member 60 along the drill. 15 With this arrangement, as soon as the material cut from the work by the drill enters the flute, it tends to travel along this rearwardly, but is removed by the projection 62 and falls upon the 20 throat 44 to be discharged. 25

The countersinking of the entrance of the drilled opening through the insole may be effected simultaneously with the drilling. For this purpose, I have shown in Fig. 2 a cylinder 40 66 having an axial passage to receive the drill and secured thereto by a set-screw 68. The outer extremity of the cylinder is inclined and is provided with countersinking teeth 70. The point at which the cylinder is attached to the 45 drill is such that when said drill has entered the work to the proper depth, the countersink in the insole will have been produced by the teeth. To prevent clogging by the accumulated chips between the cylinder 66 and the inner wall of 50 the tube 28, a helical groove 72 may be formed in the cylinder extending between its ends, this urging back the chips into the portion of the passage, which is of sufficient width to carry them freely. 55

Having described my invention, what I claim as new and desire to secure by Letters Patent of the United States is:

1. In a machine for operating upon the heel-portions of shoes, a stationary support having an auxiliary supporting portion, a rotatable tool extending outwardly from one side of the support, and a member movable upon the auxiliary portion of the support along the tool and arranged to receive about it the counter-portion of a shoe with the rear of said counter-portion resting against and positioned by the member and the sides of the counter-portion limited by it as to lateral displacement to locate the heel-seat-surface of the shoe in a predetermined relation to the tool, said member being yieldable along the tool under the influence of the positioned work. 65
2. In a machine for operating upon the heel-portions of shoes, a rotatable tool, and a work- 70

engaging member forming a part of the machine and associated with the tool, said member having substantially the transverse contour of the interior counter-portion of a shoe-upper and being movable along the tool under the influence of the work.

3. In a machine for operating upon the heel-portions of shoes, a rotatable tool, and a work-engaging member forming a part of the machine 10 and having substantially the transverse contour of the interior counter-portion of a shoe-upper, said member normally surrounding the tool and being movable along said tool under the influence of the work.

15 4. In a machine for operating upon the heel-portions of shoes, a rotatable drill, and a work-engaging member forming a part of the machine and surrounding the drill, said member having substantially the transverse contour of the interior counter-portion of a shoe-upper and normally surrounding the drill and being movable along said drill under the influence of the work.

20 5. In a machine for operating upon the heel-portions of shoes, a rotatable tool, and a work-engaging member forming a part of the machine and associated with the tool, said member having side-walls corresponding in contour to the interior counter-portion of a shoe-upper and an end-wall arranged for contact with the heel-seat-portion of the insole, the member being movable along the tool by the contact of a shoe with the end-wall.

25 6. In a machine for operating upon the heel-portions of shoes, a rotatable tool, a member movable along the tool by engagement with the work, and means movable upon the member for locking said member against movement.

30 7. In a machine for operating upon the heel-portions of shoes, a rotatable tool, a work-engaging member corresponding in shape to the heel-portion of a last, said member being movable along the tool, and a member for locking the last-shaped engaging member against movement, such locking member being movable upon 35 the engaging member.

40 8. In a machine for operating upon the heel-portions of shoes, a rotatable tool, a work-engaging member corresponding in shape to the heel-portion of a last, said member being movable along the tool, and a locking lever fulcrumed upon the engaging member and releasable by contact with the counter-portion of a shoe being operated upon.

45 9. In a machine for operating upon the heel-portions of shoes, a rotatable tool, a work-engaging member corresponding in shape to the heel-portion of a last, said member being movable along the tool, and means movable upon the member for varying the relation of the applied work to the tool.

50 10. In a machine for operating upon the heel-portions of shoes, a rotatable tool, a member movable along the tool by engagement with the work, means movable upon the member for locking said member against movement, and means movable upon the locking means for varying the relation of the engaged work to the tool.

55 11. In a machine for operating upon the heel-portions of shoes, a rotatable tool, a work-engaging member corresponding in shape to the heel-portion of a last, said member being movable along the tool, a locking lever fulcrumed upon the engaging member, and a screw threaded into the lever and arranged for contact with the work.

60 12. In a machine for operating upon the heel-

portions of shoes, a rotatable drill, and a work-engaging member forming a part of the machine and movable along the drill, said member having side-walls corresponding in contour to the interior counter-portion of a shoe-upper and an end-wall arranged for contact with the heel-seat-portion of the insole, the member having a passage opening through the end-wall and through which the drill passes.

10 13. In a machine for operating upon the heel-portions of shoes, a rotatable drill, a work-engaging member movable along the drill and having side-walls corresponding in contour to the interior counter-portion of a shoe-upper and an end-wall arranged for contact with the heel-seat-portion of the insole, said member having a passage opening through the end-wall and through which the drill passes, and a countersink secured to the drill within the passage.

15 14. In a machine for operating upon the heel-portions of shoes, a rotatable drill, a work-engaging member movable along the drill and having side-walls corresponding in contour to the interior counter-portion of a shoe-upper and an end-wall arranged for contact with the heel-seat-portion of the insole, said member having a passage opening through the end-wall and through which the drill passes, and a counter-sink having a cylindrical body secured to the drill and in which is a helical groove extending between the ends of the body, said countersink being arranged to operate in the passage in the member with the groove delivering chips to said passage.

20 15. In a machine for operating upon the heel-portions of shoes, a rotatable drill, a work-engaging member surrounding the drill, and a clearing device for the drill, said device being free to move longitudinally of the drill within the work-engaging member.

25 16. In a drilling machine for shoes, a support, a tube extending from the support, a drill rotatable in the tube, and a shoe-entering block movable longitudinally of the tube.

30 17. In a drilling machine for shoes, a support, a tube extending from the support, a drill rotatable in the tube, a shoe-entering block movable longitudinally of the tube, and a spring surrounding the tube and interposed between the support and block.

35 18. In a drilling machine for shoes, a support, a tube extending from the support, a drill rotatable in the tube, a shoe-entering block movable longitudinally of the tube, a spring surrounding the tube and interposed between the support and block, and a member for locking the block against spring-compressing movement, said member being movable upon the block for contact with the support.

40 19. In a drilling machine for shoes, a support, a tube extending from the support, a drill rotatable in the tube, a shoe-entering block movable longitudinally of the tube, a spring surrounding the tube and interposed between the support and block, a member for locking the block against spring-compressing movement, said member being movable upon the block for contact with the support, and a shoe-engaging screw threaded into the locking member.

45 20. In a drilling machine for shoes, a support, a tube extending from the support, a drill movable in the tube, and a shoe-entering block guided upon the support for movement longitudinally of the drill and having a tube extending within the support-tube.

21. In a drilling machine for shoes, a support, a tube extending from the support, a drill movable in the tube, a shoe-entering block guided upon the support for movement longitudinally of the drill and having a tube spaced from the support, and a spring carried about the tubes and interposed at its ends between the support and block.
22. In a drilling machine for shoes, a support, a tube extending from the support, a drill movable in the tube and provided with a flute, a shoe-

entering block guided upon the support for movement longitudinally of the drill and having a tube extending within the support-tube, and a clearing device carried in the block-tube and acting upon a flute of the drill.

23. In a drilling machine for shoes, a support, a rotatable drill extending through the support, a shoe-entering block yieldable upon the support longitudinally of the drill, and a latch for separately retaining the block upon said support.

FRANCIS L. BRANDT.
